DESIGN FOR A BRACELET OR LIKE ARTICLE

Charles H. Kestenman, Providence, R. I., assignor to Kestenman Bros. Mfg. Co., Providence, R. I., a corporation of Rhode Island

Application March 25, 1942, Serial No. 106,328

Term of patent 14 years

To all whom it may concern:

Be it known that I, Charles H. Kestenman, a citizen of the United States, residing in the city of Providence, county of Providence, and State of Rhode Island, have invented a new, original, and ornamental Design for a Bracelet or like Article, of which the following is a specification, reference being had to the accompanying drawing, forming a part thereof.

Fig. 1 is a top plan view of a bracelet embodying my new design and showing it partly broken away at its center;

Fig. 2 is an edge view of the bracelet also shown as broken away at the center;

Fig. 3 is a bottom plan view of the bracelet shown as broken away at the center;

Fig. 4 is a plan view showing a plurality of the links of the bracelet stretched in expanded relationship; and

Fig. 5 is an enlarged perspective view of one of the ornamental links of the bracelet.

The present design comprises a bracelet consisting of a plurality of connected links, each link having a flat top in the shape of a rhomboid and circular-shaped, downwardly inclined facets at the ends thereof substantially as shown.

I claim:

The ornamental design for a bracelet or like article, substantially as shown and described.

CHARLES H. KESTENMAN.
